SLIDE FASTENER STRINGER TAPE

Noel J. Poux, Meadville, Pa., assignor to Talon,
Inc., a corporation of Pennsylvania

Application February 2, 1942, Serial No. 429,231

6 Claims. (Cl. 139—384)

1

This invention relates to slide fasteners and, in particular, to the provision of new and improved slide fastener stringer tapes.

The stringers of slide fasteners comprise tapes each having a beaded or reinforced edge upon which is secured a row of closely spaced interlocking members. A pair of these tapes, connected at least at one end, and provided with a cam-like device known as a slider supported slidably on the rows of interlocking fastener members, form a slide fastener. Sliding movement of the slider progressively engages and disengages the fastener members to connect and disconnect the stringers for closing and opening the fastener. The tapes are usually connected adjacent the lower ends of the rows of interlocking fastener members, and means is usually provided at the upper ends of the rows of interlocking fastener members to limit upward movement of the slider and maintain it on the rows of fastener members. The bottom end connection may be a "regular" bottom stop, fixed to provide permanent connection of the lower stringer ends, or it may comprise a separable end fitting, well known in the art.

For instance, in Fig. 1, I have illustrated a fastener comprising a pair of stringer tapes 50 with reinforced inner edge portions 51 having rows of interlocking fastener members 52 secured to the reinforced inner edge portions 51. Top stops 53 are secured to the reinforced edges 51 adjacent the upper end of each row of interlocking fastener members 52 and a conventional bottom stop 54 secured to the reinforced edges 51 adjacent the lower ends of the rows of interlocking fastener members secures these tapes together at their lower ends.

The slider 55 is supported by the rows of interlocking fastener members 52 and functions progressively to close the fastener by engaging or meshing the interlocking fastener members 52 when it is drawn away from the bottom stop 54 toward the top stop 53, while progressively disconnecting or unmeshing the interlocking fastener members 52 when moved in the opposite direction, with respect to the tape, to open the fastener.

For reasons well-known in the art it is desirable to provide stringer tapes with a curvature, or fixed radius, whereby the reinforced or beaded edge portion of the stringer tape, which supports the interlocking fastener members, is of less length than the other, or outer, edge portion of the stringer tape, which latter edge portion, or a third

2

intermediate portion, is stitched to a garment or other support.

According to this invention, I secure an inherent, or permanent, fixed radius in stringer tapes by varying the interlacings of the weft threads from side to side of the tape in order that the outer edge portion or zone shall be substantially longer than the intermediate portion or neutral zone, as well as the inner, reinforced or beaded edge portion or zone of the tape. This is achieved totally without the application of differential tensions, by the loom, upon the constituent tape threads.

The interlacings or, in other words, the points where the adjacent weft threads cross are more concentrated in the region along one edge of the tape. That is to say, such crossings are greater in number per unit of area or per unit of length along the outer edge of the tape, thereby providing a greater pile-up of the weft threads along that edge than in other portions of the tape, whereby the tape in its natural condition will assume a curve due to the fact that the greater pile-up of the weft threads in this outer area or edge portion tends to lengthen the outer edge of the tape. The term "pile-up" as used herein, means the positioning of succeeding weft threads in side-by-side relation, a term well known to those skilled in the art of weaving. It will be understood that the greater the pile-up, the greater is the overall width of any particular group of weft threads (measured lengthwise of the tape).

In addition to the above variation in the tape weave from side to side of the tape, I may, optionally, weave into the tape a plurality of laterally spaced longitudinal cords or warp cords of relatively great diameter, which cords form a sewing guide unaffected by dyeing or other treatment and which aid in sewing a fastener into a garment or the like, which cords also zone the tape width or divide it into various zones having different weaves, and which cords impart to the stringer tape substantial tensile strength and durability without substantially impairing the flexibility of the tape because of the relatively great transverse spacing of these cords.

Since the diameter of these warp cords is substantially greater than that of the warp threads in the tape, adjacent (over and under) weft threads passing over these cords are more nearly perpendicular to one another than similar weft threads passing over the smaller warp threads. Thus the warp cords accentuate or exaggerate the curvature of the tape (lessening or shortening the fixed radius) since the packing or telescoping

tendency of adjacent (over and under) weft threads lessens as they approach 90 degrees with respect to one another, thereby resulting in a greater pile-up of the weft threads against each other in the vicinity of these warp cords. In other words, the combined width of a pair of such adjacent weft threads at the point of crossing or interlacing (measured lengthwise of the tape) increases as the angle between them (measured through the plane of the tape perpendicular thereto) increases, and it naturally follows that the pile-up of the weft threads increases as such angle increases.

These warp cords, as well as the warp and weft threads of the tape, are preferably of the same material throughout the tape, not abnormally twisted and are woven at normal weaving tension, whereby the fixed radius is permanent and substantially unaffected by wetting, dyeing, drying, heating, or other treatment. Furthermore, the effectiveness of the longitudinal cords in achieving the above-described guiding function is permanent, independent of color, and unaffected by subsequent dyeing, bleaching or other like treatments to which the tape may be subjected.

These and other objects and advantages of the invention will appear from the following description taken in conjunction with the accompanying drawings which form a part thereof, and will be pointed out in the appended claims.

In the drawings:

Fig. 1 is a plan view of a slide fastener having stringer tapes embodying the principles of this invention;

Fig. 2 is an enlarged diagrammatic plan view of a fragment of stringer tape constructed according to this invention;

Fig. 3 is a section taken on the line 3—3 of Fig. 2 and showing the first pick or course of the weave shown in Fig. 2;

Fig. 4 is a view similar to Fig. 3, but taken on the line 4—4 of Fig. 2 and showing the second pick of the weave;

Fig. 5 is a view similar to Figs. 3 and 4, but taken on the line 5—5 of Fig. 2 and illustrating the third pick of the weave;

Fig. 6 is a weave similar to Figs. 3, 4 and 5, but showing the fourth pick of the weave; and

Fig. 7 is a view similar to Figs. 3, 4, 5 and 6, but taken on the line 7—7 of Fig. 2, identical with Fig. 3, and showing the recurrence of the first pick after the fourth pick of the weave.

While the principles of this invention are readily applicable to fastener stringer tapes made of various materials, of widely varying specifications, and with interlocking fastener member supporting edges reinforced in various ways as, for instance, by edge reinforcement cords sewed on opposite sides of the tapes adjacent the inner edge, I have herein illustrated one embodiment of my invention embodying woven-in cord edge reinforcements.

In this embodiment, illustrated in Figs. 1-7, the tape is provided at its inner, fastener member supporting edge, with a reinforcement comprising six woven-in longitudinal cords 1, 2, 3, 4, 5 and 6, three at each side of the tape, the cords 1, 2 and 3 at one side having a right-hand twist and the cords 4, 5 and 6 at the other side having a left-hand twist, as shown by the arrows in Fig. 3. This tape is also provided with four longitudinal warp cords 7, 8, 9 and 10 which divide the tape transversely into three zones, two of these cords 9 and 10 being located adjacent one another at the outer edge of the tape to secure

desired strength and extreme length per unit (by number) of weft threads or picks. The weaves in the respective zones are varied in order that the length per unit (by number) of weft threads or picks shall increase substantially progressively from the inner to the outer edge of the tape.

In addition to the above described ten reinforcing cords or warp cords 1-10, the tape includes 24 warp threads designated 11-34 inclusive. The first eight of these warp threads (11-18) are disposed in the inner zone of the tape, which zone is defined by the inner edge reinforcement formed by cords 1-6 at one side and the longitudinal warp cord 7 at the other side. Seven of these warp threads (19-25) are disposed in the intermediate or neutral zone between warp cords 7 and 8 and the remaining nine of these warp threads (26-34) are disposed in the outer zone between the warp cord 8 and the outer edge reinforcement formed by the warp cords 9 and 10.

The main function of the inner zone (which includes the inner edge reinforcing bead comprising the six woven-in cords 1, 2, 3, 4, 5 and 6) is to support the interlocking fastener members securely while at the same time permitting substantial freedom and flexibility in order that they shall mesh and unmesh with least strain upon the tape and with least resistance to meshing and unmeshing.

The main function of the outer zone of the tape is to provide an extension for the inner zone making manipulation of the stringers convenient and aiding in attachment to garments and the like while, at the same time, functioning to maintain an inherent "fixed radius" in the tape whereby the inner zone or inner edge portion shall be shorter than the outer zone or outer edge portion.

The function of the intermediate or neutral zone is to provide connection between the active inner and outer zones as well as to provide a portion of the tape particularly adapted to receive the stitches securing the tape to a garment or support. In addition, a further and important function of the intermediate or neutral zone is to provide an intermediate portion shorter than both the outer zone and inner zone in order to maintain sufficient fullness in the inner zone to achieve desirable flexibility of the interlocking fastener members whereby to protect them against destructive strains tending to remove them or impair the security of their attachment to the tape, or cause damage to the tape adjacent the reinforced inner edge thereof. Thus, in each series of four picks in the illustrated embodiment, there are eight interlacings in the inner zone as will hereinafter most clearly appear, while there are but seven interlacings in the intermediate or neutral zone and twelve interlacings in the tape radius maintaining outer zone of the tape.

It is, of course, to be understood that where the fastener is of extremely small size and the strains to which it is subjected are extremely slight, the weaves may be changed to make the sum of the interlacings in each series of picks uniformly progressive from the inner edge to the outer edge of the tape, as, for instance, to provide eight interlacings in the inner zone, ten interlacings in the intermediate or neutral zone and twelve interlacings in the outer zone of the tape. This secures ultimate flatness of the tape and freedom from puckering or ruffling in the inner zone.

The tape is woven from a continuous weft

thread generally designated 40 and, since each of the repeated units of the weave is formed of four picks or courses, these picks or courses are designated 41, 42, 43 and 44. The first pick is designated 41 (Figs. 3 and 7); the second is designated 42 (Fig. 4); the third is designated 43 (Fig. 5); and the fourth pick is designated 44 (Fig. 6), the first pick 41 recurring after the fourth pick 44, as shown in Figs. 2 and 7.

The weave of the first pick 41 is shown in Fig. 3. This weave is generally "over one and under one" throughout and the weft thread 40 passes under the outer edge reinforcement cord 10, over the outer edge reinforcement cord 9, then under each of the warp threads 34, 32, 30, 28 and 26 and over the alternate warp threads 33, 31, 29 and 27 in the outer zone. The weft thread then passes over the reinforcement cord 8 and thence under the warp threads 25, 23, 21 and 19 and over the alternate warp threads 24, 22 and 20 in the second, intermediate or neutral zone. The weft thread then passes over the reinforcement cord 7 and under the warp threads 18, 16, 14 and 12 and over the alternate warp threads 17, 15, 13 and 11 in the inner or fastener member supporting zone. The weft thread then passes over the cord 3, under cord 2 and over cord 1 in the bead of the reinforced inner edge.

In the second pick 42, as shown in Fig. 4, the weave is generally "over two and under two." The weft thread 40 passes over the edge reinforcement cord 4, under cord 5 and over cord 6 in the bead. Thence it passes over the warp thread 11, under threads 12 and 13, over warp threads 14 and 15, under warp threads 16 and 17 and over warp thread 18 in the inner zone. The weft thread then passes over the cord 7 and under warp threads 19 and 20, over warp threads 21 and 22, under warp threads 23 and 24 and thence over warp thread 25 in the intermediate or neutral zone. Thence the weft thread passes over the reinforcement cord 8 and then under warp threads 26 and 27, over warp threads 28 and 29, under warp threads 30 and 31, over warp threads 32 and 33, and thence under warp thread 34 in the outer zone. The weft thread then passes over the reinforcement cord 9 and under the reinforcement cord 10.

In the third pick 43, as shown in Fig. 5, the weave is generally "over one and under one" as in the first pick. The weft thread 40 passes around and over the outer edge reinforcement cord 10 and under the reinforcement cord 9, thence over and under alternate warp threads in the outer zone or, in other words, over warp threads 34, 32, 30, 28 and 26 and under the alternate warp threads 33, 31, 29 and 27 in the outer zone. The weft thread then passes under the reinforcement cord 8 and "over one and under one" throughout the intermediate or neutral zone, passing over and under alternate warp threads in the neutral zone, that is, over warp threads 25, 23, 21 and 19 and under the alternate warp threads 24, 22 and 20. The weft thread then passes under the reinforcement cord 7 and over and under alternate warp threads in the inner zone or, in other words, over warp threads 18, 16, 14 and 12 and under the alternate warp threads 17, 15, 13 and 11. Thence, in this third pick 43 the weft thread 40 extends from under the warp thread 11 over cord 3, under cord 2 and over cord 1 in the bead.

In the fourth pick 44, as shown in Fig. 6, the weave is generally "over two and under two," as in the second pick. The weft thread 40 extends

from under the cord 1 around and under the cord 4, over cord 5 and under cord 6 in the bead. It extends thence under the warp thread 11, over warp threads 12 and 13, under warp threads 14 and 15, over warp threads 16 and 17, and under warp thread 18 in the inner zone. Thence the weft thread passes under the reinforcement cord 7 and over warp threads 19 and 20, under warp threads 21 and 22, over warp threads 23 and 24 and under warp thread 25 in the intermediate or neutral zone. Thence the weft thread passes under the reinforcement cord 8 and over warp threads 26 and 27, under warp threads 28 and 29, over warp threads 30 and 31, under warp threads 32 and 33, and over warp thread 34 in the outer zone. The weft thread then passes under outer edge reinforcement cord 9 and over the outer edge reinforcement cord 10, as shown in Fig. 6.

The first pick 41 then recurs since the weft thread then passes around and under the outer edge reinforcement cord 10, over outer edge reinforcement cord 9 and under warp threads 34, 32, 30, 28 and 26 and over the alternate warp threads 33, 31, 29 and 27 in the outer zone. The weft thread then passes over the reinforcement cord 8 and under warp threads 25, 23, 21 and 19 and over the alternate warp threads 24, 22 and 20 in the intermediate or neutral zone. Thence the weft thread 40 passes over the reinforcement cord 7 and under warp threads 18, 16, 14 and 12 and over alternate warp threads 17, 15, 13 and 11 in the inner zone. The thread then passes over the inner edge reinforcement cord 3, under cord 2 and over and around cord 1, as shown in Figs. 3 and 7 whereupon the second pick recurs followed by the third pick, then the fourth pick, etc.

As indicated in Figs. 4-7 inclusive by the symbol "X," between the first and second picks (Fig. 4) two interlacings occur in the inner zone, i.e., one between warp threads 13 and 14 and the other between warp threads 17 and 18. Likewise, in the intermediate or neutral zone two interlacings occur, one between warp threads 20 and 21 and the other between warp threads 24 and 25. In the outer zone two interlacings occur, one between the warp threads 27 and 28 and the other between warp threads 31 and 32.

As shown in Fig. 5, between the second and third picks two interlacings occur in the inner zone, one in the intermediate or neutral zone and four in the outer zone. In the inner zone the interlacings occur between the warp threads 11 and 12 and between warp threads 15 and 16. In the intermediate or neutral zone the interlacing occurs between the warp threads 22 and 23. In the outer zone the interlacings occur between the reinforcement cord 8 and the warp thread 26, between warp threads 29 and 30, between warp threads 33 and 34, and between warp thread 34 and the outer edge reinforcement cord 9.

Between the third and fourth picks, as shown in Fig. 6, two interlacings occur in the inner zone, two in the intermediate or neutral zone and two in the outer zone. In the inner zone the interlacings occur between warp threads 13 and 14 and between warp threads 17 and 18. In the intermediate or neutral zone the interlacings occur between warp threads 20 and 21 and between warp threads 24 and 25. In the outer zone the interlacings occur between warp threads 27 and 28 and between warp threads 31 and 32.

As shown in Fig. 7, between the fourth pick 44

and recurring first pick 41, two interlacings occur in the inner zone, two in the intermediate or neutral zone and four in the outer zone. In the inner zone the interlacings occur between warp threads 11 and 12 and between warp threads 15 and 16. In the intermediate or neutral zone the interlacings occur between the reinforcement cord 7 and warp thread 19 and between warp threads 22 and 23. In the outer zone the interlacings occur between the reinforcement cord 8 and warp thread 26 and between warp threads 29 and 30, between warp threads 33 and 34, and between warp thread 34 and reinforcement cord 9.

From the above it will clearly appear that in each series of four picks the number of interlacings occurring in the inner zone between the bead and the reinforcement cord 7 is:

$$2(\text{Fig. 4}) + 2(\text{Fig. 5}) + 2(\text{Fig. 6}) + 2(\text{Fig. 7}) = 8$$

Likewise, the number of picks occurring in the intermediate or neutral zone is:

$$2(\text{Fig. 4}) + 1(\text{Fig. 5}) + 2(\text{Fig. 6}) + 2(\text{Fig. 7}) = 7$$

And the number of interlacings occurring in the outer zone is:

$$2(\text{Fig. 4}) + 4(\text{Fig. 5}) + 2(\text{Fig. 6}) + 4(\text{Fig. 7}) = 12$$

Thus, since there are more interlacings in the outer zone than in the inner zone the length per unit of picks is greater in the outer than in the inner zone and the tape, by this weave, is given an inherent fixed radius or curvature which will not be affected by wetting, drying or dyeing. Because there are no differential stresses in the weave, shrinkage will be substantially uniform throughout and will not affect this curvature. It is also to be noted that three interlacings occur in the outer edge reinforcement in each series of picks, namely, none between the first and second pick (Fig. 4), one between the second and third pick (Fig. 5), one between the third and fourth pick (Fig. 6) and one between the fourth pick and recurring first pick (Fig. 7). Due to the fact that the reinforcement cords 9 and 10 have a greater thickness or radius than the warp threads 1—34, resulting in a greater area of contact where the weft threads cross or interlace, the piling up is greatest in these outer edge reinforcement cords, which is extremely desirable because the outer edge reinforcement imparts to the tape a substantial part of its structural strength and because it is, obviously, desirable that the tape shall be longest at its outer edge.

In the embodiment illustrated, the variation in length between the outer and intermediate zones imparts the fixed radius to the tape and the excess length of the inner zone over that of the intermediate zone provides fullness in the inner zone whereby the necessary flexibility of support of the fastener members is achieved. As pointed out above, the relation of zone lengths may be varied, as desired, whereby the length of the tape (as a whole) varies progressively from the inner to the outer edge of the tape, where such fullness is not desired. Other variations are, of course, comprehended, as, for instance, elimination of the cords or various zoning arrangements other than that illustrated.

It is, of course, to be understood that the above description is merely illustrative and in no wise limiting and that I desire to comprehend within my invention such modifications as are included within the scope of the appended claims.

Having thus fully described my invention,

what I claim as new and desire to secure by Letters Patent is:

1. In a slide fastener tape, a plurality of longitudinally extending warps including one or more of relatively large size along the outer edge of the tape and weft threads extending across the tape and interwoven therewith, the interlacings or crossings of said weft threads being more concentrated in the region of said large cords resulting in a greater pile-up of the weft threads along that edge than in the other portions of the tape, whereby a curve is imparted to the tape without resort to abnormal tensions or twists of the warp threads.
2. In a tape for slide fasteners of the class described, a plurality of longitudinally extending relatively small warp threads, a plurality of relatively larger warp threads arranged along one or the inner edge of said tape so as to provide a beaded edge therealong for attachment of fastener elements thereto, one or more relatively large warp threads arranged along the opposite or outer edge of said tape and at least another relatively large warp thread arranged intermediate the edges so as to divide the tape into a plurality of longitudinally extending zones, and a continuous weft thread interwoven back and forth, through and between all of said warp threads, each pick of said weft threads extending substantially throughout the width of the tape and interwoven in such a manner that the interlacings or crossings of the weft threads with the warps are more concentrated in the zone between the intermediate larger warp thread and the outer edge than in the zone between the intermediate larger warp thread and the inner or beaded edge, thereby resulting in a greater pile-up of the weft thread in the area or zone along the outer edge portion of the tape than in the zone or area along the inner edge portion thereof, whereby a natural curved tape having a fixed radius is provided.
3. In a tape for slide fasteners of the class described, a plurality of longitudinally extending relatively small warp threads, a plurality of relatively larger warp threads arranged along one or the inner edge of said tape so as to provide a beaded edge therealong for attachment of fastener elements thereto, one or more relatively large warp threads arranged along the opposite or outer edge of said tape, a plurality of similar relatively large warp threads arranged intermediate the edges of the tape and spaced from each other so as to divide the tape into a plurality of longitudinally extending zones, and a continuous weft thread interwoven back and forth through and between all of said warp threads, each pick of said weft threads extending substantially throughout the width of the tape with the weft threads interwoven in such a manner that the interlacings or crossings of the weft threads with the warps are more concentrated in the zone between the outer edge and the adjacent intermediate relatively large warp thread than in any of the other zones thereby resulting in a greater pile-up of the weft thread in the area or zone along the outer edge portion of the tape than in any other zone or area whereby a natural curved tape having a fixed radius is provided.
4. In a slide fastener tape, a plurality of longitudinally extending warps and weft threads extending across the tape and interwoven therewith, each pick of said weft threads extending substantially throughout the width of the tape,

alternate picks of the weft threads extending over one and under one of the warps and the pick of the weft threads between said alternate weft threads extending over two and under two of the warps except in that portion of the tape along the outer edge thereof where said weft threads extend over one and under one of the warps in each pick with the weft threads and warps along the outer edge portion being constructed and arranged so that the interlacings or crossings of the weft threads along the outer edge portion are more concentrated than in any other portion of the tape, thereby resulting in a greater pile-up of the weft threads along that edge portion than in the other portions of the tape, whereby a natural curve is imparted to the tape without resort to abnormal tensions or twists of the warps.

5. In a slide fastener tape, a plurality of warp threads including a plurality of relatively large warp threads along one edge and at spaced points intermediate the edges, and weft threads extending across the tape and interwoven therewith, each pick of said weft threads extending substantially throughout the width of the tape, 10 said weft threads being interwoven with the warps in such a manner and the weft threads and warps being constructed and arranged so that the interlacings or crossings of the weft threads along the outer edge of the tape are 15 20 25 30

more concentrated along the outer edge portion than in any other portion of the tape, thereby resulting in a greater pile-up of the weft threads along that edge portion so that said outer edge is greater in length than the other portions of the tape, whereby a natural curve is imparted to the tape without resort to abnormal tensions or twists of the warps.

6. In a slide fastener tape, a plurality of longitudinally extending warp threads and a plurality of relatively large warp threads along the inner edge to provide a beaded edge for attachment of fastener elements, a pair of such larger warp threads along the opposite or outer edge, and a plurality of such larger threads spaced apart intermediate the edges so as to provide guide lines dividing the tape into at least three zones, weft threads extending across the tape and interwoven therewith, each pick of said weft threads extending substantially throughout the width of the tape, said weft threads being interwoven with the warps in such a manner that the interlacings or crossings of the weft threads with the warps are more concentrated in the zone along the outer edge portion than in the other zones, thereby resulting in a greater pile-up of the weft threads in said outer zone, whereby a fixed radius curve is imparted to the tape without resort to abnormal tensions or twists of the warps.

NOEL J. POUX.
